DEXTER E. PEASE AND GEORGE RICHARDS, OF RICHLAND CENTRE,
WISCONSIN.

Letters Patent No. 88,203, dated March 23, 1869.

IMPROVEMENT IN SELF-REGISTERING LUMBER-MEASURE.

The Schedule referred to in these Letters Patent and making part of the same.

To all whom it may concern:

Be it known that we, DEXTER E. PEASE and GEORGE RICHARDS, of Richland Centre, in the county of Richland, and in the State of Wisconsin, have invented certain new and useful Improvements in Lumber-Measure; and do hereby declare that the following is a full, clear, and exact description thereof, reference being had to the accompanying drawings, and to the letters of reference marked thereon.

The nature of our invention consists in the construction and arrangement of a device by which the number of square feet in different lengths of timber can be computed at one and the same time.

In order to enable others skilled in the art to which our invention appertains, to make and use the same, we will now proceed to describe its construction and operation, referring to the annexed drawings, which form a part of this specification, and in which—

Figure 1 is a side view;

Figure 2, a bottom view;

Figure 3, a top view;

Figure 4, a bottom view, showing a different arrangement; and

Figure 5, a side view of the same.

A represents the handle, to the end of which is pivoted a disk, B.

This disk is grooved, on its bottom, or under side, with a series of grooves, marked respectively from eight to twenty, according to the length of the timber which is to be measured. These grooves are all circular, and have a common centre, namely the pivot of the disk; and the face of the disk is provided with a series of circles, corresponding with the grooves on the bottom side. Each of these circles is divided into as many equal parts as the corresponding groove is marked.

The outer periphery of the disk B, which is exactly one foot, is divided into twelve equal parts, each thus being an inch in length.

All the circles on the face of the disk are so divided, that the last number of each will come at the point indicated by a straight line drawn from the centre of the disk to the point where the figure 12, at the periphery, is placed.

To the handle A, is a stationary finger, or indicator, C, secured, which points along the face of the disk B, for a purpose that will be hereinafter set forth.

To the handle A, is also attached an adjustable spring-arm, D, which extends along the same and under the disk B; and to the end of said spring, under the disk, is pivoted a small wheel, E, which, with the spring-arm D, is so arranged, that the wheel can be placed in any of the circular grooves on the under side of the disk.

A cog-wheel, F, which has sixty cogs, is also pivoted to the spring-arm D, in such a manner, that a pin, a, which is placed on the wheel E, will turn the cog-wheel F one cog at each revolution it makes.

The wheel E is divided in ten equal parts, and the

cog-wheel F is marked so that the cogs can be easily counted.

The operation of the device is as follows:

Set the disk B so that the twelve-inch line shall come directly under the pointer, or index C. The small wheel E is to be set so that the small pin a shall have just passed out of the cog on the cog-wheel F, which it turns; and this latter so set that the cog No. 60 shall come opposite a pin, b, on the spring-arm D, to which the wheels are attached. If it is desired to measure eight-feet lumber, the small wheel E is placed in the smallest groove, marked 8. Take by the handle and put the large wheel, or disk B, so that the pointer, or index C shall be at the edge of the board. Then bear on it sufficiently hard to turn the wheel, and run it across the board till the index shall come to the other edge, and in the same manner with the next.

It will be seen that in so turning the disk B, the smaller wheel E is turned by the friction, and at each revolution of the same, the pin a turns the cog-wheel F the distance of one cog.

After measuring the eight-feet boards, and it is desired to measure, in addition, boards, say, fourteen feet in length, the wheel E is raised out of the groove marked 8, and placed in the one marked 14, and then go on as before. And so in the case with any other length.

When done, to find the number of square feet measured, annex a cipher to the number of the cog opposite the pin b, on the spring, to which add the number of feet indicated by the board-measure on face of the disk. For example, if cog 42 is at the pin, or point b, that indicates four hundred and twenty square feet, by annexing a cipher; and if the index C is at 10, on the periphery of the wheel B, and the length of the board last measured is twelve feet, look at the number on circle 12, corresponding with 10 on the periphery, which is also 10, then add that to the four hundred and twenty, which makes four hundred and thirty square feet of lumber measured.

Instead of having grooves on the under side of the disk B, we may provide it with a series of circular flanges, as shown in figs. 4 and 5, where the different parts are marked, respectively, A', B', D', and E'.

Having thus described the construction and operation of our lumber-measure, we will now briefly state the principle upon which the same is constructed.

We take the friction-wheel E, running in groove marked 10, upon which we base our calculations. The diameter of both this friction-wheel and the groove marked 10, is one and one-half inch, so that at each revolution of the measuring-wheel B, with the friction-wheel in said groove, gives the friction-wheel one revolution, which moves the index-wheel F one cog, denoting ten square feet of lumber measured. Two revolutions would give two cogs, or twenty square feet.

Now, the ratio of the diameters of the grooves, or projections, for each additional foot in length of the

lumber to be measured, above ten, is fifteen one-hundredths of an inch greater than the groove marked 10, which we have taken as a standard. So that, for eleven feet, a groove one and sixty-five one-hundredths of an inch in diameter would be required; for twelve feet in length, a circle, or groove of one and eighty one-hundredths of an inch in diameter; thirteen feet, one and ninety-five one-hundredths of an inch in diameter; fourteen feet, two and ten one-hundredths of an inch; and so on up to twenty feet in length, when the diameter should be three inches, or twice the diameter of the groove which indicated the ten feet. For shorter lengths than ten, the grooves should be correspondingly less in size.

The grooves which should be marked by odd numbers, we did not deem it necessary to show, as what is shown and described, fully illustrates the principle.

The wheel E, which, as above described, is turned by friction, may be provided with cogs on its edge, for turning.

The wheel, or disk B, may be provided, on its under side, with a pin, c, arranged, in connection with a spring, d, on the handle, in such a manner that every time the indicator C points at No. 12, on the disk, it will give notice to the operator.

Having thus fully described our invention,

What we claim as new, and desire to secure by Letters Patent, is—

The arrangement of the handle A, disk B, spring-arm D, friction-wheel E, and index-wheel F, all constructed as described, and operating substantially as and for the purposes herein set forth.

In testimony that we claim the foregoing, we have hereunto set our hands, this 31st day of August, 1868.

DEXTER E. PEASE.
GEO. RICHARDS.
